United States Patent Office.

JAMES OLD, OF PITTSBURG, PENNSYLVANIA.

Letters Patent No. 96,342, dated November 2, 1869.

FIRE-PLACE GRATE.

The Schedule referred to in these Letters Patent and making part of the same

To all whom it may concern:

Be it known that I, JAMES OLD, of Pittsburg, in the county of Allegheny, and State of Pennsylvania, have invented a new and useful Improvement in Grates; and I do hereby declare the following to be a full, clear, and exact description thereof, reference being had to the accompanying drawing, making a part of this specification, in which—

Figure 1 is a rear or inside perspective view of a fire-place grate, with my improvement attached;

Figure 2 is a sectional view, in perspective, of one of the connections;

Figure 3 is a sectional view of a fire-place and grate, with my improvement attached thereto; and

Figure 4 is a side view of the link-piece.

Like letters of reference indicate like parts in each.

In Letters Patent, issued to me 16th March, 1869, for an improvement in grates, a tilting-bar is shown as extending along between the rear of the grate and the back tile of the fire-place, with devices for operating it, the object of it being to stir or break up the mass of coal which is apt to settle in the back part of the fire-space, and supply it with air, so as to promote its combustion.

The object of my present invention is to provide means for attaching, easily and effectively, such a tilting-bar to the ordinary form of grate, so as to apply it to grates already set, as well as to grates when being set, but which have not been fitted, in casting, with the appliances shown and described in the patent above referred to.

The nature of my invention consists in attaching the tilting-bar, and the devices for operating it, to the grate or fire-basket, by means of one or more link-pieces, each of which has an 'eye' at one end, for the bearings of the tilting-lever, and an eye or hook at the other end, and below the grate-bars, for the insertion of a key, or other equivalent device in lieu thereof.

To enable others skilled in the art to make and use my invention, I will proceed to describe its construction and mode of operation.

The grate or fire-basket a' a'' is made of my approved form, and, when in use, is set in a fire-place, (as seen in fig. 3,) b representing the ash-pit, b' , the fire-space, d , the rear wall, c , the back tile of the fire-space, and c' , the dust-flue.

Between the rear bottom-bar a' and the back tile c , I arrange a tilting-bar, e , which, by a shifting-lever, e' , attached thereto, is raised and lowered to and from the positions shown in fig. 3.

The uses of this bar, and also of the stirring-plates e'' , which operate up and down between the bar a , are set forth in the patent already issued to me.

In order to be able to attach these devices to the grates in ordinary use, and when in use, I provide one or more of the stirring-plates e'' e' , with journal or bearing-pins s , each of which rests on the adjacent bar a , and projects beyond it far enough to enter an eye in the upper end of the link-piece m .

One of these link-pieces m is inserted on each of the bearings s , and extends down between and far enough below the bars a for the insertion of a key, s' , in an eye in its lower end, or in a hook, x , as shown, the shape of the two being such, that the key s' , with a wedge-like action, will bear firmly on the hook, and hold the devices firmly in place.

Instead of the hook x and key s' , any mechanical equivalent thereof may be used, such as a screw-bolt and nut, or a pin with a button attached.

The link-piece m , also, may be made of T-shape, as shown in fig. 4; and the projecting ends of the T-head, on either side, may rest on the bars a , in which case, the pins s need only be made long enough to enter them, and give a secure bearing therein.

An ordinary grate can then be furnished with the appliances described, and all the usefulness of the tilting-bar and stirring-plate be secured therewith.

Another feature of my invention consists in pivoting the bearing-pins s above the grate-bars a , instead of below, as in my former patent, the effect of which is, that the tilting-bar e will be caused to act on the fuel in the rear part of the fire-basket more nearly in a vertical direction, and, when it is raised, an increased amount of air-space will be secured, as at n n' .

What I claim as my invention, and desire to secure by Letters Patent, is—

1. The link-piece m , keyed, or fastened in other equivalent manner, to the bars a , and carrying, by bearings s , a tilting-bar, e , the parts named being combined substantially in the manner set forth.

2. The arrangement of the link-pieces m , with the grate-bars a , so as to effect the pivoting of the bearings s above the grate-bars, instead of below.

In testimony whereof, I, the said JAMES OLD, have hereunto set my hand.

JAMES OLD.
